UNITED STATES PATENT OFFICE.

EDWARD SAMUEL WELLS, OF IPSWICH, QUEENSLAND, AUSTRALIA.

BUTTER-CUTTING MACHINE.

No. 925,542.

Specification of Letters Patent.

Patented June 22, 1909.

Application filed October 31, 1908. Serial No. 460,558.

To all whom it may concern:

Be it known that I, EDWARD SAMUEL WELLS, a subject of the King of the United Kingdom of Great Britain and Ireland, resident of Moffatt street, Ipswich, in the State of Queensland, Commonwealth of Australia, have invented a certain new and useful Improved Butter-Cutting Machine, of which the following is a specification.

10 This invention relates to a butter cutting machine its object being to expeditiously and accurately cut up the contents of a butter box into blocks of one pound each or of any other desired weight, thereby saving the 15 loss entailed by the retailer in cutting and patting the butter into blocks.

The invention consists of a wooden frame, a number of wires stretched across the top from side to side and from front to back, a 20 plate for receiving the butter contents of a butter box, a base plate adapted to be raised and lowered by wheels fixed to an axle revolving in the framework underneath the base plate and by chains or ropes fixed to the 25 wheels and to the base plate, traveling over grooved pulleys in the top of the frame.

To fully describe the invention reference is now made to the drawings in which:—

Figure 1 is a front elevation of the machine. Fig. 2 side elevation of same. Fig. 3 plan of base plate and posts of frame. Fig. 4 detail on enlarged scale of raising and lowering gear. Fig. 5 perspective view of machine. Fig. 6 plan of frame showing the cross wires on top. Fig. 7 perspective view of butter plate showing slots spaced correspondingly to the wires. Fig. 8 section of top frame showing chamfered edges. Fig. 9 a plan view of wire strainers on enlarged scale. Fig. 10 a perspective view of wire strainers on enlarged scale. Fig. 11 is an elevation of one of the guiding bars for the transverse wire 19; Fig. 12 is an end view showing said guiding bar in position and with the block 22 thereon; Fig. 13 is a bottom view of the block; Fig. 14 is a detailed view showing the bolt to which the wire 19 is secured.

The reference numerals indicate like parts in all figures.

50 1 are four vertical posts, mortised or otherwise fixed to which is the top frame 2 across this frame are stretched stationary cutting wires 3 and 3^a only some of which are figured, these wires are sunk in slots just below the 55 surface of the top frame as seen in Figs. 1 and

2 and are fastened at one end to a rod 23 screwed to the frame on one side and to wire strainers 24 on the other side. As shown in Fig. 8 the bottom edges of the frame 2 are chamfered so as to guide the block of butter 60 in the event of the said block not being squarely set upon the butter plate.

4 is a base plate sliding up and down between the posts and fixed thereon are two under cut rails 4^a: to the underside of the 65 base plate is screwed a guide bar 4^b having its ends turned down at right angles which impinge against the sides of the posts as seen in Fig. 2.

5 is a pointer and 5^a a graduated scale for 70 adjusting the size of butter blocks to required weight.

6 is a butter plate preferably of marble provided with V shaped slots 6^a, which is 75 screwed down to a bed plate 7 on the underside of which are fastened guide rails 7^a which slide between the rails 4^a of the base plate: the V shaped slots allow the stationary wires to pass right through the block of butter.

8 is an axle revolving in cross pieces 9 provided with necessary collars to keep same in position, 11 are grooved pulleys, and 12 a milled edge wheel keyed to axle, the latter being for regulating the cut and 14 a handle 85 for revolving the axle. 15 wire ropes attached to pulleys 11 traveling over grooved pulleys 16 in top frame, the other ends of which are attached to the base plate 4 by which it is raised and lowered.

90 17 is a channel bar screwed to top of frame through the slot of which passes a square shanked screw pin 18 to which is fastened a lateral cutting wire 19 strained across the top frame by the screw pin inserted through the 95 slot 20 of the channel bar and a screwed knob 21, screwed up against a sliding block 22.

In using the invention a block of butter from a butter box is placed upon the butter plate which is then raised to the position of the lateral cutting wire which is drawn across the block cutting off a shaving and leaving the top perfectly level, it is then further raised until the pointer on the base plate 100 points to the respective marks on the graduated scale, the lateral cutting wire is then drawn or pushed through the butter cutting the block laterally, it having been cut vertically by the stationary wires on top of frame, 105 110

the small blocks or prints are then removed and the base plate further raised for the next cut.

Having now described my invention, what I claim as new and desire to secure by Letters Patent is:—

1. A butter cutting machine comprising a supporting frame, a top frame supported therein, said top frame having its center 10 open, wires carried by said top frame and extending across the opening, the bottom edges of said top frame around the opening being chamfered to guide the butter block, a supporting plate within the supporting frame, 15 and means for moving the plate vertically.

2. A butter cutting machine comprising a supporting frame, a top frame therein, slotted channel bars carried by said top frame, blocks sliding in said channel bars, a 20 lateral cutting wire carried by said blocks, and a vertically movable butter supporting frame.

3. A butter cutting machine comprising a supporting frame, a top frame therein, 25 slotted channel bars carried by said frame, blocks sliding in said channel bars, screw pins

carried in said blocks, a lateral cutting wire fastened to said pins, screw knobs on said pins and a vertically movable butter supporting plate.

4. In an improved butter cutting machine, the combination of a wooden frame, a base plate, a butter plate provided with V shaped slots across the face, a bed plate, rails on the underside of same, sliding between rails on the base plate, an axle revolving in bearers beneath the base plate, grooved wheels keyed to said axle, ropes attached to said wheels, traveling over grooved pulleys in the top frame and fastened to the base plate, said 40 wheels and ropes adapted to raise and lower the base plate, a milled edge wheel keyed to said axle and an arresting pawl pivoted to said frame as herein described and illustrated by drawings.

In witness whereof I have hereunto set my hand in presence of two witnesses.

EDWARD SAMUEL WELLS.
